DESIGN FOR A BROILER

Herbert H. Minard, Wichita, Kans.

Application March 25, 1935, Serial No. 56,032

Term of patent 3½ years

To all whom it may concern:

Be it known that I, Herbert H. Minard, a citizen of the United States of America, residing at Wichita, in the county of Sedgwick and State of Kansas, have invented a new, original, and ornamental Design for Broiler, of which the following is the specification, reference being had to the accompanying drawing, forming a part thereof.

I claim:

The ornamental design for a broiler as shown. In testimony whereof I affix my signature.

HERBERT H. MINARD.
